Benjamin Roman.
Attorney.

UNITED STATES PATENT OFFICE

2,379,807

HAIR CURLER

Harry H. Klein, Woodhaven, N. Y.

Application July 3, 1943, Serial No. 493,346

2 Claims. (Cl. 132—43)

This invention relates to a hair curler of the type which comprises a flexible bar, around the middle portion of which the strand of hair is wound to produce the curl, and the end portions of the bar are then bent over the wound hair to secure the curled strand in place.

These hair curlers, usually consisting of a flat metallic bar covered by a braided textile fabric, have inherent objections in that they possess undue weight and that their bent over ends do not efficiently grip the wound up hair.

The principal object of the invention is to provide an improved hair curler having reduced weight and enhanced hair gripping efficiency, and that will be furthermore simple, inexpensive, strong, more durable, conveniently and economically manufacturable, and rendered more conveniently and efficiently utilizable.

Other objects and advantages will hereinafter appear.

In the accompanying drawing—

Fig. 1 is a plan view showing the indefinite length of flexible bar entering into the making of the hair curler.

Fig. 2 is an end elevation of the bar shown in Fig. 1.

Fig. 3 is a plan view of the bar shown in Fig. 1 as it appears during manufacture of the curler.

Fig. 4 is a front elevational view of the bar shown in Fig. 3.

Fig. 5 is an end elevation, in an enlarged scale, of the bar shown in Fig. 3.

Fig. 6 is a plan view of the bar shown in Fig. 3 as it appears after it is covered by a braided textile fabric.

Figs. 7 and 8 are a plan and front elevational view, respectively, of the hair curler constituting the invention.

Fig. 9 is an end elevational view of the completed hair curler, in an enlarged scale, shown in Figs. 7, 8.

Fig. 10 is an illustration of the hair curler, as it appears when in operative condition of gripping the strand of hair in wound up state.

In the making of the hair curler there is utilized an indefinite length of a flat flexible metallic bar 1, Fig. 1, of transverse cross-sectional configuration shown in Fig. 2, and said bar is compressed laterally at interval regions 2, thereby forming a series of portions 3, Figs. 3, 4, 5, 50 each of which is narrowed at its middle part 4, toward which tapers the uncompressed parts 1a of the bar, as seen in Fig. 3. In transverse cross-sectional configuration, and in a plane perpendicularly to that of the flatness of the bar 1, the middle part 4 is thickened by the said lateral compression thereof, relatively to the thickness of the bar 1, thereby attaining the configuration and

form seen in Figs. 4, 5. In addition to so compressing and forming the bar 1 at the interval regions 2, it is coated by a tube 5 of braided textile fabric, as shown in Fig. 6, and severed transversely at the middle of said regions on parts 4, as indicated by the dash-and-dot lines, into segments 6 shown in Figs. 7, 8, each segment thus constituting the completed hair curler. As the cross-sectional area 7, Fig. 9, of each part 4 has a shorter perimeter than that of the flat initial bar 1, the braided tubular fabric 5, which is in stretched state upon the main body of the bar, contracts to the configuration of the regions 2 before severance of the bar, Fig. 6, and to that of the tapered ends 8 of the severed segment 6, Fig. 7. Due to said contracting action of the braided ends 5a of tube 5 upon the tapered ends 8 of the curler 6, it tends to prevent unraveling of the braiding and prevents the segmental bar therewithin from longitudinal displacement relatively thereto, although adhesive material may be resorted to between bar 1 and the braiding 5 for further attainment of these purposes.

In utilizing the hair curler, the strand of hair 11 is wound around its median portion 6a, as shown in Fig. 10, and its end portions 8 are bent over to bear pressingly upon the wound tuft 11a of the hair, as indicated. Due to the aforesaid forming and thickening of the end portions 8 they are rendered firm and much strengthened, and their securing hold upon the hair tuft 11a to maintain it against unwinding is greatly increased, thereby permitting a considerable shortening of the portions required for bending over the hair, and consequently resulting in a lightening and reduction of the total weight of the hair curler. By the same improvements the durability of the hair curler is also enhanced, and owing to the form and thickening of the end portions 8 the bending manipulations of the hair curler, incident to the winding of the hair strand and removal of the curler, are much facilitated.

Variations may be resorted to within the scope of the invention.

Having thus described my invention, I claim:

1. A hair curler having the combination of a flexible flat metallic bar, said bar having each of its end portions tapered in the plane and contour of its width and thickened in a plane perpendicularly to said width, and said bar being covered by an envelope.

2. A hair curler comprising a flexible flat metallic bar, and said bar having each of its end portions narrowed in the plane of its width and thickened in a plane perpendicularly to said width.

HARRY H. KLEIN.
